UNITED STATES PATENT OFFICE.

URBAN JOEDICKE, OF ST. LOUIS, MISSOURI.

DUST-COLLECTOR.

935,658.

Specification of Letters Patent. Patented Oct. 5, 1909.

Application filed June 29, 1908. Serial No. 440,982.

To all whom it may concern:

Be it known that I, URBAN JOEDICKE, citizen of the United States, residing at St. Louis, State of Missouri, have invented certain new and useful Improvements in Dust-Collectors, of which the following is a full, clear, and exact description, reference being had to the accompanying drawings, forming a part hereof.

10 My invention has relation to improvements in dust collectors for vacuum-cleaning systems; and it consists in the novel arrangement and construction more fully set forth in the specification and pointed out in

15 the claim.

In the drawings, Figure 1 is a combined vertical section and elevation of my improved collector; Fig. 2 is a horizontal plan and section on the broken line 2—2 of Fig. 20 1; Fig. 3 is an enlarged sectional detail showing the different layers of the strainer; Fig. 4 is an enlarged sectional detail of the safety-valve; and Fig. 5 is a cross section on line 5—5 of Fig. 4.

25 The object of my invention is to construct a dust collector which shall possess a durable and effective strainer for the dust-laden air passing therethrough; one in which the strainer shall be stiff and whose component parts are readily replaced; one having a dust receptacle independent of the strainer proper; and one possessing further and other advantages better apparent from a detailed description of the invention which is

35 as follows:—

Referring to the drawings, C, represents an outer casing resting on legs L and having a top lid or cover T. Disposed within the casing beneath the cover is an annular shelf or ledge 1 from which depends the strainer presently to be described, a gasket or packing ring 2 being interposed between the supporting flanges of the shelf and strainer respectively. The strainer is composed of an outer open-work basket composed of strips a, b, intersecting each other at right angles, an inner open-work basket composed of strips a', b', the inner faces of the respective baskets being provided with wire-gauze linings or diaphragms, or equivalent foraminous material d. Between the baskets is a

filling e of hair, or other fibrous material as shown.

The upper ends of the strips a, a', are provided with outwardly bent flanges 3, to the outer series of which is bolted the annular ring 4 by which one end of the space between the baskets is closed, the bolts 5 securing said ring to the basket, likewise securing the latter to the supporting flange of the shelf 1, the packing ring 2 being likewise pierced by the bolts (Fig. 3). The opposite end of the space between the baskets is closed by a filler-block 6, the adjacent ends of the outer strips a projecting a suitable distance beyond said filler-block, and being screw-threaded on the inner face for collectively engaging the outer screw-threaded surface of the dust receptacle 7 which is itself screwed to the basal flange of the casing C (Fig. 1). The receptacle has a removable bottom D.

The casing is provided with a safety-valve 8 controlled by a spring 9 encircling the stem 10 thereof between the casing wall and terminal head 11 of the valve-stem.

In the operation of the invention a current of air is drawn through the pipes P, P' and through the apparatus as shown by the arrows in Fig. 1, the pipe P leading to a vacuum pump, and the pipe P' leading to the suction-head of a vacuum cleaning system as well understood in the art. The dust-laden air is drawn into the strainer, and in its passage through the successive layers d, e, d of wire gauze, hair and wire gauze is cleansed of its dust and dirt, which latter is deposited at the bottom of the receptacle 7. Should the vacuum in the casing become too great so as to endanger the collapse of the walls of the casing C, the valve 8 will yield to atmospheric pressure and allow some air to enter the casing.

Having described my invention, what I claim is:—

In a dust-collector, a casing in combination with a strainer composed of inner and outer open-work basket spaced a suitable distance apart and depending from the inner walls of the casing, the walls of said baskets being formed of intersecting series of strips, a filling of hair between the baskets, foraminous sheets or linings secured to the inter-

secting strips, a receptacle secured respectively to the casing and to the lower terminals of the vertical series of strips of the outer basket, and means for drawing a current of dust-laden air into and out of the casing, and through the strainer, substantially as set forth.

In testimony whereof I affix my signature, in presence of two witnesses.

URBAN JOEDICKE.
